UNITED STATES PATENT OFFICE

WILLIAM A. J. KREAGER, OF DENVER, COLORADO, ASSIGNOR, BY MESNE ASSIGNMENTS,
TO BARQUE ROYALTY, INC., OF DENVER, COLORADO, A CORPORATION OF COLORADO

BOILER

Application filed June 1, 1929. Serial No. 367,665.

This invention relates to improvements in boilers of the type employed in connection with the production of low pressure steam for heating buildings and for the production of hot water for use in hot water heating systems and for similar purposes.

It is the object of this invention to produce a boiler which shall be adapted to burn, either gas or liquid fuel and which shall be so constructed that it will have a very large thermal efficiency so that practically all of the heat values of the fuel will be transferred to the water.

This invention, briefly described, consists in a boiler which has been shown as formed by flat parallel sides or ends that are connected by a semi-circular top. Located within the boiler is a steel tube of cylindrical shape which forms the combustion chamber and which is secured to one of the end plates of the boiler. The inner end of this combustion chamber terminates in a header from which a plurality of flues extend parallel with the combustion chamber to a point near its other end where they connect with an annular header. The interior of this header is connected with a second header located below and from this the flue passages for the combustion gases extend in a zigzag direction to the outlet which is near the bottom of the boiler. The feed water is admitted near the bottom so as to come in contact with the flues near the point where the gases leave the boiler. The water which enters near the bottom of the boiler passes upwardly between and along the flues and as it ascends, it absorbs heat from the hot flues and is constantly coming in contact with heating surfaces of higher temperature, until it reaches the wall of the combustion chamber which, of course, is of higher temperature than any of the flues. By the arrangement just described, the feed water will come in contact with the coldest flue surfaces and will become gradually heated as it passes upwardly so as to come in contact with the more highly heated surfaces and in this manner a uniform temperature gradient will be maintained between the water and the heating surfaces throughout the boiler.

Having thus briefly described the invention, I will now proceed to describe the same in detail and for this purpose reference will be had to the accompanying drawings, in which the preferred embodiment of the invention has been illustrated, and in which:

Fig. 1 is a vertical section through the boiler, taken on line 1—1, Fig. 3;

Fig. 2 is a section through the lower header, taken on line 2—2, Fig. 1;

Fig. 3 is an end elevation of the boiler; and

Fig. 4 is a section taken on line 4—4, Fig. 1.

In the drawings reference numeral 1 represents the bottom of the boiler, while numerals 2 and 3 represent the sides. The rear end wall of the boiler has been indicated by reference numeral 4. The front of the boiler instead of being made from a single plate, is made from three separate plates which have been designated by numerals 5, 6 and 7. In the construction of the boiler forming the subject matter of this application, the several plates were electrically welded and the drawings have therefore been cross hatched so as to indicate a unitary or integral construction. The sides 2 and 3 are connected by a semicircular dome 8 in the manner shown in Fig. 4. Extending transversely of the interior of the boiler are supporting bars 9, whose ends are electrically welded to the inside of the side walls. A narrow flat plate 10 is supported on the transverse bars 9 and serves as a support for the combustion chamber and its associated headers and flues. Upwardly extending arms 11 are integrally secured to the transverse bars 9 and have their upper ends connected by means of bars 12, which cooperate with the plate 10 to form a cradle or rest for the combustion chamber and associated parts in a manner which will be described and which is apparent from the drawings. The combustion chamber is formed from an elongated cylinder 13 which extends inwardly through a hole in the plate 5 and which is electrically or otherwise autogenously welded thereto. Secured to the inner end of the cylinder 13 is a header 14 that is welded to the cylinder. A substantially annular header 15 encloses the cylinder 13 but is not

85
90
95
100

connected with the latter. Flues 16 connect the interiors of headers 14 and 15 in the manner shown. Located below the transverse bars 9 is a header 17 which is preferably 5 formed from cast iron and which is provided with three cylindrical projections 18 near its top and two similar cylindrical projections 19 near its bottom. These projections extend through openings in the plate 7 and 10 are welded to the latter. The rear wall 20 of the header 17 is provided with four rows of openings for the reception of flues 21. The two center rows are enclosed by a curved wall 22 which divides the interior of the 15 header into three compartments in the manner shown in Fig. 1. The other ends of flues 21 extend through openings in the plate 23 and are welded to the latter. Curved walls 24 form with the plate 23 two chambers the 20 upper of which receives the inner ends of the two upper rows of tubes while the lower chamber is in communication with the two lower rows of tubes. The header 15 is provided with three tubes 25 which extend 25 through openings in plate 5 and are welded to this plate. Secured to the outer ends of these tubes are elbows 26. Similar elbows are connected with the tubular members 18 and these elbows are joined by means of 30 pipes 27.

In the drawings the burner has been indicated by reference numeral 28 and the products of combustion pass inwardly through the combustion chamber and thence flow 35 through the flues 16 into the interior of the header 15 and thence through pipes 27 to the upper chamber of header 17 from which they flow through the upper row of tubes 21 to the interior of the upper chamber on plate 23 40 and return thence through the second row of tubes into the central chamber formed by the walls 22, from here the gases flow through the third row of tubes to the lower chamber on plate 23 from which they return 45 through the lowermost row of tubes to the lowermost chamber in header 17, from whence they pass outwardly through tubes 19 into a pipe which extends to the outside of the building. It will be seen from the 50 above description that the flue gases flow downwardly and are discharged near the bottom of the boiler, while the water enters the boiler and flows upwardly. It will also be seen that the combustion chamber and 55 flues are entirely surrounded by water and that the water enters at the point where the flue gases leave and therefore there is a gradual increase in the temperature of the water from the bottom towards the top so 60 that the temperature of the water varies in the same direction as the temperature of the flue gases and therefore as the water moves upwardly and becomes hotter it is continually coming in contact with surfaces that 65 are heated to a higher temperature. After

the boiler has been started in operation and the feed water supply adjusted so as to replace the water that is vaporated, the interior of the boiler will soon come to a substantially stationary position so far as temperatures 70 are concerned and the temperature of the water and of the flue gases will remain the same at all points and therefore there will be no violent fluctuations in temperature and as a consequence no corresponding changes 75 in expansion and contraction and therefore the boiler is subjected to less strain than it would be if the feed water were introduced periodically at or near the top of the boiler. 80

I want to call attention to the fact that the cylindrical combustion chamber is connected to the boiler at one end only, and that the manifold 14 rests on the upper surface of the plate 10 so that it can freely expand and contract in accordance with the temperature 85 variations to which it must necessarily be subjected. Since the cylinder 13 and the flue 16 are made of the same kind of material, they have the same coefficient of expansion and therefore it is possible to weld the tubular members 25 to plate 7 without setting up any severe strains due to the expansion and contraction. The end of member 13 is closed by a plate 29 which is held in place by means 90 of bolts 30. The boiler is provided with several openings one of which has been designated by reference numeral 31 and which serves as the discharge for steam or hot water, while openings 32 and 33 are usually plugged but can be used whenever desired. The feed 95 water opening has been indicated by reference numeral 34. 100

When oil is employed as fuel, it can be preheated by passing it through a chamber 35 that is in communication with the outer surface of one of the pipes 27. The pipe 27 can either be enclosed by means of a pipe 36 of bigger diameter so as to form an annular chamber through which the oil may pass, or a flexible copper tube 37 may be wrapped 110 around this pipe and in this manner the oil can be raised to a high temperature before it enters the burner, thereby facilitating the production of vapors. 115

From the above description it will be apparent that I have produced a boiler which is especially well adapted for use in connection with low pressures and which is so constructed that a very high thermal efficiency can be attained. The boiler is intended for use with apparatus producing a forced draft and this makes it possible to have the products of combustion travel downwardly and to have them discharged from the boiler near the bottom thereof. Practically all the heated surfaces are covered with water and therefore very little, if any, of the heat has an opportunity of escaping. The outside of the boiler can, of course, be covered with a layer 120 of heat insulating material so as to keep the 125 130

loss due to radiation at the lowest possible point.

Having described the invention what is claimed as new is:

- 5 1. A boiler having a tubular combustion chamber extending inwardly from the front end thereof, and terminating in a header located near the rear of the boiler, a hollow annular header surrounding the combustion 10 chamber near the front end of the boiler, a plurality of flues connecting the interiors of the headers, a header located beneath each of the other two, the one located beneath the annular header having a plurality of separate compartments and the one located beneath the rearmost upper header having one compartment less than the front lower header, flues interconnecting the compartments in the lower headers so that flue gases will 15 pass successively through all of the compartments, means for connecting the interior of the annular header with the upper compartment of the lower front header, and means for connecting the lower compartment of the 20 last named header with a flue gas outlet pipe located outside of the boiler.

2. A boiler having a tubular combustion chamber extending inwardly from the front end thereof and terminating in a header located near the rear of the boiler, an annular header surrounding the combustion chamber near its front end, a plurality of flues connecting the headers, a header located below each of the other two, the one located 25 near the front having an upper, a central and a bottom compartment, the one located near the rear having an upper and a lower compartment, flues connecting the upper compartment of the rear header with the upper and the central compartment of the three compartment header, and other flues connecting the lower compartment of the rear lower header with the central and lower compartments of the three compartment header, means for 30 connecting the interior of the annular header with the upper compartment of the three compartment header, and means for connecting the lowermost compartment of the three compartment header with a flue gas outlet pipe located on the outside of the 35 boiler.

3. A boiler having a plurality of transverse bars adapted to support a combustion 40 chamber, a cylindrical combustion chamber located in the boiler above the supports, the inner end of the combustion chamber terminating within the boiler and having attached to its a header, a header located near the front 45 end of the combustion chamber flues extending between and connecting the interiors of said headers, a header located beneath each of the headers mentioned above, means for connecting the interiors of the headers near 50 the front end of the boiler with each other 55

and means comprising a plurality of conduits for connecting the interior of the two lower headers.

In testimony whereof I affix my signature.

WILLIAM A. J. KREAGER.
